UNITED STATES PATENT OFFICE.

ALBERT L. COLE, OF AUBURNDALE, MASSACHUSETTS, ASSIGNOR, BY MESNE ASSIGNMENTS, TO BLOSS & WALES, INCORPORATED, OF BOSTON, MASSACHUSETTS, A CORPORATION OF NEW YORK.

TELESCOPIC PIPE-JOINT.

1,003,033.

Specification of Letters Patent. Patented Sept. 12, 1911.

Application filed October 14, 1909. Serial No. 522,621.

To all whom it may concern:

Be it known that I, ALBERT L. COLE, a citizen of the United States, residing at Auburndale, in the county of Middlesex 5 and State of Massachusetts, have invented a new and useful Improvement in Telescopic Pipe-Joints, of which the following is a specification, reference being had therein to the accompanying drawings.

10 This invention relates to telescopic pipe-joints.

The objects of the invention are to provide a joint which permits variation in the length and rotary movement of the parts 15 connected; which is so constructed that it does not require frequent repacking to keep it steam and water-tight and which is provided with flexible means for maintaining the movable member in an outward position.

20 The following is a description of the invention, reference being made to the accompanying drawings, in which:—

Figure 1 is a side elevation of the preferred form of the invention; Fig. 2 is a 25 vertical longitudinal sectional view of the same; Fig. 3 is an elevation of the closed end; Fig. 4 is a vertical transverse sectional view on line 4—4 in Fig. 2; and Fig. 5 is an end view looking toward the movable 30 member.

In the drawings illustrating the preferred embodiment of the invention 1 represents a 35 socket-member having an interior cylindrical chamber 2 closed at one end by a cap 3 provided with a thread 4 adapted to screw into the threaded end of the socket-member 1. A suitable annular gasket 5 interposed between the edge of the cap 3 and the end of the socket-member 1 serves to make the cap 40 water and steam tight. From one side of the socket-member 1, a pipe-connection 6 leads from the chamber 2. The connection may be either male or female and may be situated on the side of the socket-member 1 45 as shown in the drawings, or on the end in place of the cap 3. The other end of the socket-member 1 is provided with a circular opening of less diameter than the diameter of the chamber 2 thereby forming an interior 50 annular flange 7.

A pipe-section 10 having one end provided with a thread 11 to receive pipe connections and having a shoulder 12 located midway is movably mounted within the socket-member

1 with the threaded end projecting through 55 the open end of the said socket-member. The threaded end of the pipe-section 10 may be either male or female as occasion demands. As shown in Fig. 2 of the drawings, the shoulder 12 fits closely within the 60 cylindrical chamber 2 and the pipe-section likewise makes a close fit with the flange 7. The section 10 is free to be rotated or moved endwise within the cylindrical chamber of the socket-member. To secure a tight 65 joint between the socket-member and the pipe-section packing-rings 15 are arranged between the two adjacent to the shoulder 12 and a helical spring 16 within the chamber 2 having one end abutting the cap 3 and 70 the other abutting the packing 15 serves the double purpose of keeping the packing tight against the shoulder 12 and the pipe-section 10 in a forward position with the shoulder 12 against the flange 7. If desired, in cases 75 where there is little weight on the pipe-section and little rotary movement thereof, packing-rings may be used between the shoulder 12 and the flange 7 in addition to or even in substitution of the packing shown 80 in the drawings. Such use, however, is impracticable where the pipe-section is subjected to any degree of rotary movement since that movement, especially if the pipe-section supports any weight, grinds away 85 the packing in a very short time and requires such frequent repacking as to be of little practical value.

The inner end of the pipe-section 10 has four angular cuts 17 arranged on the inner 90 surface to receive a square-headed tool to prevent rotary movement of the same when a pipe is being screwed onto the threaded end 11 or to turn the same to make the connection if it is impossible or difficult to turn 95 the pipe to be so connected.

In the use of the joint, one of the pipes to be connected is screwed into the connection 6 or if that pipe is fixed the joint may be turned to make the connection. The 100 cap 3 is removed and a square-headed tool is inserted in the angular cuts 17 on the inner end of the pipe-section 10 and the latter may then be connected to the other pipe either by turning the pipe-section or 105 the pipe. If the latter method is used the square-headed tool is employed to hold the pipe-section 10 stationary while the con-

nexion is being made. When the joint is properly connected the cap 3 is readjusted in place.

It is to be observed that this construction permits a very free rotary movement of the pipe-section and its connections as well as an endwise or horizontal movement of considerable extent and any sudden movement of the pipe-section is taken up by the helical spring and thereby prevents the joint being injured. Another advantage of this construction is that it is unnecessary when installing new packing to cut the rings. In the operation of repacking the cap 3 is removed from the socket member, the helical spring withdrawn and the packing rings slipped over the inner end of the pipe-section 10; the spring and cap are readjusted and the packing operation is completed.

20 What I claim is:—

1. In a telescopic pipe joint, the combination with a chambered socket-member having an inner annular flange at its open end, of a pipe section rotatably mounted and longitudinally movable therein, a packing ring mounted on the inner end of said pipe-section between it and said socket-member, and compressible means abutting said packing ring to maintain a tight joint and said pipe-section in a forward position.

2. In a telescopic pipe-joint, the combination of a chambered socket-member having an inner annular flange at its open end, a pipe section rotatably mounted and longitudinally movable therein, a packing ring on the inner end of said pipe section and a spring within said socket-member bearing against said packing ring.

3. In a telescopic pipe-joint, the combination of a socket-member having an inner annular flange at its open end, a pipe-section rotatably mounted and longitudinally movable therein and provided midway with an annular shoulder, a packing ring mounted on the inner end of said pipe section and a helical spring within said socket member abutting said packing ring.

4. In a telescopic pipe-joint, the combination of a socket-member having an inner annular flange at its open end, a pipe section rotatably mounted and longitudinally movable therein and provided midway with a shoulder, a packing ring mounted on the inner end of said pipe-section between said pipe-section and said socket-member and abutting said shoulder and flexible means abutting said packing ring to maintain the same at all times against the said shoulder and to keep said pipe-section in a forward position.

5. In a telescopic pipe-joint, the combination of a socket-member having an inner annular flange at its open end, a pipe-section rotatably mounted and longitudinally movable therein and provided with an interme-

diate annular shoulder fitting the interior of said socket-member, a packing ring mounted on the inner end of said pipe-section abutting said shoulder and a helical spring abutting said packing ring to maintain said ring and said pipe-section in a forward position.

6. In a telescopic pipe-joint, the combination of a cylindrical chambered socket-member having an opening at one end smaller than its interior diameter, a pipe-section rotatably mounted and longitudinally movable therein having an intermediate annular shoulder fitting the interior of said socket-member and having one end projecting through the said opening in said socket-member, a packing ring mounted on the inner end of said pipe-section abutting said intermediate shoulder and a helical spring abutting said packing ring to maintain it in position.

7. In a telescopic pipe-joint, the combination of a cylindrical socket-member having one end provided with an interior thread and the other end with an interior shoulder, a threaded cap closing the threaded end of said socket-member, a pipe-section rotatably mounted and longitudinally movable within said socket-member with one end projecting through the open end thereof and having an intermediate annular shoulder fitting the interior of said socket-member, a packing ring mounted on the inner end of said pipe-section abutting said annular shoulder and a helical spring abutting at one end said cap and at the other end said packing ring.

8. In a pipe-joint, the combination of a socket-member, a pipe-section rotatably mounted and longitudinally movable therein and projecting through the open end thereof, said pipe-section being provided with an intermediate annular shoulder fitting the interior of said socket-member and said socket-member having an interior shoulder at its open end to prevent the withdrawal of said pipe-section, a packing ring mounted on the inner end of said pipe-section between it and the socket-member and abutting said intermediate shoulder, a cap threaded into the other end of said socket-member to close the same and a spring abutting said cap and said packing to maintain the latter in close contact with said intermediate shoulder and to normally maintain said pipe section in a forward position.

9. In a pipe-joint, the combination of a socket-member having an inner shoulder at its open end, a pipe-section rotatably mounted therein and capable of longitudinal movement, said pipe-section having an intermediate annular shoulder fitting the interior of said socket-member and normally abutting said inner shoulder on said socket-member, a packing ring mounted on the

- inner end of said pipe-section between the latter and the socket member, a cap screw-threaded into the other end of said socket-member to close the same and a helical 5 spring abutting said packing and said cap to maintain said packing against the intermediate shoulder of said pipe-section and to normally maintain said pipe section in a forward position.
- 10 10. In a pipe joint, the combination of a socket member having an inner annular flange at its open end, a pipe-section rotatably mounted and longitudinally movable therein with one end projecting through 15 said open end of said socket-member, and having an intermediate annular shoulder fitting the interior of said socket member and normally abutting said inner annular flange on said socket member, packing on 20 the inner end of said pipe section and
- flexible means to maintain said packing against the intermediate shoulder of said pipe section and to normally maintain said pipe section in a forward position.
11. In a pipe joint, the combination of a 25 chambered socket member having an inwardly extending flange at one end, a pipe section longitudinally movable therein through said flanged end, packing at the inner end of said pipe section, and a spring 30 within the socket member bearing against said packing.
- In testimony whereof, I hereunto set my hand, in the presence of two subscribing witnesses, this the twenty fourth day of 35 September, 1909.

ALBERT L. COLE.
